COMBINED CLAMP AND ARTICLE HOLDER
Edwin R. Olila, 14840 Greenview Ave., Detroit 23, Mich.
Filed Mar. 6, 1961, Ser. No. 93,675
2 Claims. (Cl. 24—3)

This invention relates to jewelry and, in particular, to clasps.

One object of this invention is to provide a combined tie clasp and article holder, such as a tie clasp, for holding medical pills or capsules, of such construction that the user will always have immediately available a supply of such pills or capsules for use in regular medication or in an emergency.

Another object is to provide a combined tie clasp and article holder of the foregoing character wherein one arm of the clasp carries the article receptacle and the other arm serves as a closure for the receptacle.

Another object is to provide a combined tie clasp and article holder of the foregoing character wherein the arm of the clasp carrying the receptacle is resiliently urged into closing relationship with the other arm of the clasp, yet is moved away from its closed position by a simple pressure of the fingers in opening the clasp.

Another object is to provide a combined tie clasp and article holder of the foregoing character wherein one arm of the clasp normally serves as a closure for the mouth of the receptacle attached to the other arm of the clasp when the clasp is detached from the necktie or other pieces of clothing which it is intended to grip, yet which presses the latter into closing relationship with the mouth of the receptacle when the clasp is in its usual gripping position.

Another object is to provide a combined tie clasp and article holder of the foregoing character wherein the receptacle is adapted to carry relatively large articles such as pills or capsules, yet wherein the closure arm is narrower than the receptacle mouth so as to avoid excessive width and conspicuousness, but is sufficiently wide to prevent the escape of pills or capsules from the receptacle when it is detached from the thing which it is otherwise intended to grip.

Other objects and advantages of the invention will become apparent during the course of the following description of the accompanying drawing, wherein:

FIGURE 1 is a front elevation of a man's shirt and necktie with a combined tie clasp and article holder attached thereto with its top moved into a vertical plane, according to one form of the invention;

FIGURE 2 is a side elevation of the combined tie clasp and article holder of FIGURE 1, removed from the necktie and turned around end-for-end with its top uppermost;

FIGURE 3 is a longitudinal central vertical section through the holder of FIGURE 2, shown in its closed position, with pills therein;

FIGURE 4 is a view similar to FIGURE 3, but showing the holder in its open position, ready for filling;

FIGURE 5 is a cross-section taken along the line 5—5 in FIGURE 2; and

FIGURE 6 is a top plan view of a modified holder for abnormally wide or abnormally long articles, such as capsules or tablets.

Hitherto, persons suffering from certain diseases or abnormalities have been obliged to carry constantly with them pills, capsules or the like which are taken either regularly or in case of an emergency. Such persons have often been greatly inconvenienced or even gravely endangered when such an emergency arose and they could not find the necessary medicaments. Persons suffering from certain heart diseases, for example, are required to carry with them nitroglycerine pills, and diabetics are re-

2

quired to either undergo frequent injections of insulin or carry constantly with them pills or capsules giving equivalent medication. The present invention provides a combined tie clasp and article holder of such a character that when it is attached to a piece of clothing, such as a necktie, dress or the like, it is always immediately available and cannot be misplaced, so that the user has a constant supply of his medicament immediately on hand.

Referring to the drawing in detail, FIGURES 1 to 5 inclusive show a combined tie clasp and article holder, generally designated 10, according to one form of the invention as including an elongated movable arm 12 carrying an elongated cup-shaped receptacle 14 either integral therewith or, as shown, separate therefrom and secured 5 thereto in any suitable way, as by soldering, welding, casting or pressing. The cup-shaped receptacle 14 is provided with an open-mouthed recess 16 for receiving pills or other articles P (FIGURE 3). As shown in FIGURES 3 to 5, the receptacle 14 is cast in position upon 10 the movable arm 12.

The movable arm 12 is provided with upstanding ears 18 perforated to receive pivot lugs 20 extending inwardly therein from the arms of the forked end of the reversely-bent lower or inner portion 22 of an elongated fixed 15 arm 24. The fixed arm 24 has a combined clasping and outer closure portion 26 for the recess 16 of the receptacle 14, the portion 26 being bent reversely to the inner portion 22 at the turn or bend 28. Coiled around the pivot lugs 20 is a torsion spring 30 (FIGURE 4), one leg 20 of which engages the inner portion 22 of the fixed arm 24 and the other leg engages a handle portion 32 on the movable arm 12, urging the arm portions 22 and 32 away from one another so as normally to urge the mouth 25 or entrance 34 of the receptacle 14 into closing engagement with the closure portion 26.

The modified combined tie clasp and article holder, generally designated 110, shown in FIGURE 6 is generally similar to the holder 10 of FIGURES 1 to 5 inclusive, but differs in sufficient detail that it and its component parts are numbered with the same reference numerals as the holder 10, increased by 100, in order to show the relationship between the corresponding parts or components of the two holders.

The holder 110 of FIGURE 6 is intended for use with 45 capsules, pills or other articles which are longer or wider than can be conveniently received within the recess 16 of the receptacle 14 of the holder 10, yet at the same time the fixed arm 124 has been kept sufficiently narrow to be inconspicuous but sufficiently wide to prevent escape 50 of the capsules or other articles C contained in the cavity or recess 116 of the receptacle 114. The holder 110 of FIGURE 6 is otherwise of similar construction to the holder 10 of FIGURES 1 to 5 inclusive and has the same manner of use and operation.

In the operation of the holder 10 of FIGURES 1 to 5 inclusive or the modified holder 110 of FIGURE 6, the operator grasps the holder between his thumb and forefinger, pressing the handle portion 32 of the movable arm 12 and the top or closure portion 26 of the fixed arm 24 55 toward one another into the open position shown in FIGURE 4, winding up the torsion spring 30 while so doing. He then inserts the pills P (FIGURE 3) or capsules C (FIGURE 6) in the recess 16 or 116 of the receptacle 14 or 114 respectively and then releases his grip 60 upon the arm portions 26 and 32. The spring 30 then urges the mouth 34 of the receptacle 14 or the corresponding receptacle 114 of FIGURE 6 into closing engagement with the closure portion 26 of the fixed arm 24.

If the user desires to apply his clasp or holder 10 65 or 110 to an article of clothing, such as a necktie T (FIGURE 1), he preferably lifts the portions of the necktie into a horizontal position before opening the holder

10 and inserting the necktie T between the fixed arm portion 26 and the mouth 34 of the receptacle 14 or 114, so as to avoid letting the pills P or capsules C roll out of the recess 16. He then releases his grip upon the arm portions 26 and 32 or the corresponding arm portions of the holder 110 of FIGURE 6, whereupon the spring 30 urges the necktie portions T into closing engagement with the mouth 34 of the recess 16 or 116 against the arm portion 26 or 126 as an abutment.

To withdraw one of the articles, such as a pill or capsule, the user reverses the procedure described above by again grasping the arm portions 26 and 32 between his thumb and forefinger, pressing them together to move the arm portion 26 or 126 away from the tie T, whereupon the latter can be pulled away from the holder 10 or 110 or vice versa, and the pill P or capsule C removed and used.

What I claim is:

1. A combined necktie clasp and article holder comprising
an elongated forward clasp arm of a length sufficient
to extend across the major part of the width of the
necktie,
a rearward clasp arm having a length substantially
shorter than said forward clasp arm,
said forward clasp arm having a forward portion
adapted to extend across the necktie and a rearward
portion bent reversely thereto and extending from
one end thereof toward said rearward clasp arm,
means pivotally connecting said rearward portion of

5
10
15

said forward clasp arm to said rearward clasp arm, an elongated cup-shaped article receptacle secured to one of said arms and having a recess therein with a mouth facing the other arm,
said receptacle having a side wall extending around said recess with a portion thereof disposed between said recess and said pivotal connecting means,
said arms being movable relatively to one another into recess-closing and recess-opening positions respectively,
and resilient means for urging said arms toward one another into recess-closing position.

2. A combined tie clasp and article holder, according to claim 1, wherein said receptacle is secured to said rearward arm with its mouth facing said forward arm.
